UNITED STATES PATENT OFFICE.

GEORGE T. EAGER, OF RIDGEWOOD, NEW JERSEY.

DISPLAY DEVICE FOR VEILING AND THE LIKE.

1,238,898.

Specification of Letters Patent.

Patented Sept. 4, 1917.

Application filed May 31, 1916. Serial No. 100,775.

To all whom it may concern:

Be it known that I, GEORGE T. EAGER, a citizen of the United States, residing at Ridgewood, in the county of Bergen and State of New Jersey, have invented certain new and useful Improvements in Display Devices for Veiling and the like, of which the following is a full, clear, and exact description.

10 This invention relates to improvements in devices to be utilized in selling veiling and similar transparent fabrics.

In the sale of veiling it has been the general practice to roll the veiling upon bolts. 15 A customer, in buying, frequently looks at a large number of these bolts and in order to decide which veil material is suitable carries the bolt to a looking-glass and looks through a portion of the veil which has 20 been temporarily unrolled from the bolt. This procedure takes considerable time and, as the bolts are usually returned to the sales person unrolled, additional time is required to roll up the material and replace the bolts 25 on the shelves. This frequent handling of the veiling often soils, tears and otherwise damages the material so that it is unsalable.

The above considerations have made veiling departments unprofitable in many stores, 30 since the overhead expense is extremely high in proportion to the profits accruing from the sales made.

Veiling manufacturers have also found it a difficult matter to suitably trade-mark their 35 veils, as the material itself is of so open a texture that labels can not be properly applied thereto, nor can labels be printed on the edge of the material.

The objects of this invention reside in the 40 provision of means to obviate the before-mentioned difficulties, attendant upon the sale of veiling and similar materials. The particular means which I employ will be described in the accompanying specification, 45 shown in the drawing, and more particularly pointed out in the appended claims.

In the drawings:

Figure 1 shows, in plan, a veiling bolt 50 with my improved veil display slide inserted therein.

Fig. 2 shows a view similar to Fig. 1 but with the one wall of the bolt cut away to show the veil carrying slide. Portions of the slide are broken away to show the construction.

Fig. 3 shows a central sectional view of Fig. 2.

Fig. 4 is a sectional view taken on line 4-4 of Fig. 2 and shows the opaque back portion of the slide. 60

Fig. 5 is a sectional view taken on line 5-5 of Fig. 2 and shows in section the window aperture in the slide.

In more detail, in the drawings, the bolt, upon which the veiling is to be wrapped is 65 of flattened tubular form having side walls 10 and 11 suitably spaced apart at the edges by edge strips 12. These edge strips 12 and walls 10 and 11 define a slot 13 open at both ends of the tube which is adapted to receive 70 a slide 14. The slide is rounded at the ends with tabs 15 upon which the trade-mark, stock number, and other desired data can be marked as shown in Fig. 1. To facilitate the insertion of the slide in the bolt, one 75 of the walls of the bolt is slightly cut away as shown at 15a.

The slide 14 is preferably made of two pieces of cardboard, 16 and 17, gummed together by gum strips 18. The back piece 17 80 comprises an upper opaque portion 19 which has thereon the representation of a face as shown in Fig. 2. The lower part of the back piece has a window aperture cut there-through defined by edges 20 in Figs. 2, 3 and 85 5. The front part 16 of the slide 14 has a single large window aperture defined by edges 21 and of such size as to expose both 90 the representation of a face on the upper part of the slide and the window in the lower part thereof. A sample piece of the veiling 22 is stretched in position between the back and front parts 16 and 17 and thereafter is held firmly by the gum strips 18 when the two sections of the slide are 95 pressed together. It will be understood that the representation of a face is not essential. If desired this representation of the face may be omitted. The object of this part is to provide a suitable background against 100 which the material may be examined and it will be apparent that this background may be of any desired color depending upon the color of the veiling displayed.

In use the sales person removes the bolts 105 from the shelves and first pulls out the slide 14 from the top to disclose to the customer the veiling over the opaque back portion or over the representation of the face as the case may be. From this preliminary ex- 110

atmination the customer can frequently determine whether the veiling is at all suitable. If the customer wishes to examine the veiling more critically, *i. e.* to look through it into a mirror, the sales person either partially withdraws the slide from the other end of the bolt so that the customer can look through the veiling appearing over the window, or the slide may be entirely removed and handed to the customer. It is also possible for the slide to be almost entirely withdrawn from the upper end of the bolt if it is desired to inspect the veiling in this manner.

By the use of this device the sale of veiling and similar materials may be facilitated as will be well understood. Furthermore manufacturers can identify a veiling with a particular trade-mark and in this way educate their customers to demand a particular make of veiling.

It will be understood that the customer may also hold the veil displaying slide against any desired background such as cloth. In this way the customer can determine exactly how a particular sample of veiling chiffon, net, etc., will appear when used in a garment over such cloth.

I claim:—

1. A display device for veiling and the like, comprising a slide adapted to be slidably inserted in a bolt and having an aperture therein, said slide having provisions for receiving a sample of the veiling and for permanently displaying the same over an aperture therein of such dimensions and contour as to permit a human visage to be inspected therethrough, whereby a person may determine the appearance of the veiling when the same is placed in front of a face, and said slide having a back-ground portion adjacent the window aperture to permit an inspection of the veiling against a back-ground, said window aperture and back-ground being relatively so disposed as to permit of concurrent inspection through the window and against the background.

2. A display device for veiling and the

like, comprising a slide adapted to be inserted within a bolt carrying a veiling, said slide having an opaque back portion against which the veiling may be inspected and a window aperture through which the veiling may be inspected, said slide having provision to secure the said veil in adjustment over the opaque back portion and window aperture.

3. A display device for veiling and the like, comprising a veil displaying slide adapted to be slid within the bolt carrying the veiling, said slide having an opaque back portion having a representation of a face thereon over which a sample of veiling may be inspected and a window aperture in said slide through which the veiling may be inspected.

4. A display device for veiling and the like, said device comprising, in combination, a member having provision to receive and retain a sample of veiling, a window aperture in said member through which the veiling carried by the member may be inspected, and an opaque back-ground portion on said member and adjacent the window aperture against which the veiling may be inspected, said window aperture and back-ground being relatively so disposed as to permit of concurrent inspection through the window and against the background.

5. A display device for veiling and the like, comprising a slide adapted to be inserted in and removed from a bolt carrying the veiling, said slide having a back portion and a front portion, said back portion having an opaque portion and a window aperture, and the front portion having a window aperture exposing the opaque portion and the aforesaid window in the back portion, said front and back parts of the slide being adapted to receive a piece of veiling therebetween whereby said veiling may be inspected against a background and in front of a mirror substantially as described.

In testimony whereof I affix my signature,

GEORGE T. EAGER.
